UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,137,904.

Specification of Letters Patent.

Patented May 4, 1915.

Application filed July 11, 1914. Serial No. 850,301.

To all whom it may concern:

Be it known that I, JOHN R. ROGERS, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter returned through distributing mechanism to the magazine from which they started.

20 More particularly, it relates to that kind thereof equipped with a plurality of magazines and means whereby any selected one thereof may be brought into operative relation to the assembling devices.

25 One of the principal features of my invention is the arrangement of a single keyboard mechanism connected in part to each of several magazines, so that matrices may be delivered from any one of them by the 30 operation of the corresponding keys, without the manipulation of additional selecting or connecting mechanism.

35 My improvements further comprise means whereby this keyboard mechanism may be connected in part to each of several magazines, as before mentioned, or in its entirety to a single magazine.

40 These and other features, together with means for accomplishing the desired results, 45 will be described more at length in the following specification and finally pointed out in the claims.

45 Among the advantages derived from this arrangement is the ability to carry a full 50 font of matrices, such as the ordinary ones, in one magazine, and to divide a font of larger matrices, such as display or head let-

ter matrices, between a plurality of magazines, all in the same machine. Hitherto it has not been practicable to equip machines 55 like the commercial "Model 8" and "Model 9" linotypes with both ordinary and head letter or display faces.

60 In the accompanying drawings, I have shown my invention as applied to the style of machine illustrated in U. S. Letters Patent to J. R. Rogers, No. 848,771, dated April 2, 1907, and No. 930,693, dated August 10, 1909. In this particular construction, the magazines are stationary and a portion of 65 the assembling devices are movable so as to be brought into operative relation to the selected one. However, it will be seen that the invention may be similarly applied to machines wherein the assembling mechanism 70 is stationary and the magazines movable relatively thereto.

75 I have shown my improvements only in preferred form and by way of example, and as adapted to the particular machine designated, but obviously many changes and variations may be made therein, and in their mode of application, which will still be comprised within the spirit of the invention. Similarly, they may be applied to other 80 forms of typographical machines, such as typesetters, typecasters and the like, which handle type or dies, instead of matrices. Generally speaking, I desire it to be understood that I do not limit myself to any 85 specific form or embodiment, except in so far as such limitations are specified in the claims.

85 Referring to the drawings: Figure 1 is a front view of a portion of the machine; Fig. 90 2 is an enlarged section on the line 2-2 of Fig. 1; Fig. 3 is a perspective detail of the escapements, etc.; and Fig. 4 is a front detail elevation of the same parts.

95 The matrices X are as usual stored according to font in the several magazines A¹, A², A³, A⁴, four such magazines being illustrated by way of example, although it will be understood that the same principles may be applied to a greater or a smaller number. 100 Each of the magazines is equipped with a series of escapements B¹, B², B³, B⁴, respectively, the operation of which effects the delivery of the matrices in the desired order.

The actuating means for the escapements comprise the reed C, which are movable vertically by the ordinary keyboard mechanism, including the levers C¹, secondary 5 reeds C², etc., selected and controlled from the keys D. In the particular form illustrated, the magazines are stationary and the escapement actuating devices are shifted vertically so as to register them with the 10 escapements of the selected magazine, and horizontally to connect them with and disconnect them from the escapements. The connecting and disconnecting means comprise the elements E, which are movable 15 horizontally by the engaging means E¹, both being mounted in and carried by the frame F, which may be moved vertically by the engaging means F¹. These respective horizontal and vertical movements are effected 20 and controlled through connections F² to the manually operated lever G. The parts so far described, and their mode of operation, are or may be substantially similar to those embodied in the Model 9 linotype, or as set 25 forth in the previously mentioned Rogers patent.

As the matrices are released from the selected magazines, they pass into the race-way H and thence to the other assembling 30 devices in the customary manner. In the Rogers patents, the frame F is provided with a bridge constituting a support or guide for the matrices as they pass from the selected magazine to the raceway. In the present instance, I provide the frame with two receiving elements in the form of superposed throats H¹ and H², which are brought simultaneously into register with two magazines, as the frame F is adjusted to different 35 positions. The lowermost throat H² is the substantial equivalent of the former bridge, and the uppermost one H¹ is supplemental thereto under the conditions subsequently outlined.

40 When it is desired to equip the machine with head letter or display fonts, in addition to those ordinarily employed, the latter may be stored in the lower magazines, and the former in the upper ones, although this arrangement may be reversed if desired. The magazines ordinarily employed are of insufficient size to receive a full font of these larger matrices, and therefore it becomes necessary to divide it between two or 45 more magazines. For instance, in the drawings, the two upper magazines A¹ and A² are shown as containing a font of these large matrices, half in one and half in the other, while the two lower magazines A³ and A⁴ 50 each contain a single font of the ordinary matrices.

If it be desired to employ matrices from either of the lower magazines, the frame F is adjusted to register the throat H² with the

selected one, and the reeds C with the escape- 65 ments thereof. This operation is effected in the usual manner, and in this position of the parts, the matrices are released therefrom by the operation of the keys D, and then pass through the throat H² into the race- 70 way H.

If it be desired to employ the larger matrices stored in the two upper magazines A¹ and A², the frame F is adjusted to the position shown in Fig. 2, when the matrices pass 75 through either the throat H¹ or H², according to the magazine in which they are stored. However, to control the operation of the escapements of both magazines from the single set of keys D requires a novel arrangement of the actuating devices, which will 80 next be described.

Assuming, for purposes of illustration, that the upper font comprises ninety matrices, forty-five of which are contained in 85 each of the magazines A¹ and A², provision is made for the actuation of forty-five escapements B¹ and forty-five escapements B² from the single set of keys D. To this end, the respective escapements B¹ and B² 90 are preferably arranged in different vertical planes and in staggered relation to each other, as best shown in Fig. 4. Each of the upper series of escapements B¹ is provided with a suitably guided depending link or 95 slide J, of sufficient length to locate its lower end in operative relation to a reed C,—the arrangement and location of the parts being such (Figs. 3 and 4) that the lower ends of the links or slides J and outer ends of the 100 escapements B² will be alternated, and located in suitable relation to the single bank of reeds C, which may be regarded as divided into two alternated sets. For instance, as shown in Fig. 4, the actuation of the second, fourth and sixth of the reeds, effects the 105 operation of the first, second and third escapements B² of the magazine A², and the consequent release of the matrices containing the characters "e", "a", "i"; while the 110 actuation of the third, fifth and seventh of the reeds, through the corresponding links or slides J, effects the operation of the second, third and fourth escapements B¹ of the magazine A¹, and the consequent release of 115 the matrices containing the characters "t", "o", "n".

It will be seen that by the proper storage and location of the larger matrices in the upper magazines, the ordinary arrangement 120 of the keys D need not be altered, and that it is equally applicable, whether they are connected to one magazine containing a single font, or to a plurality of magazines with a font divided among them. Further, 125 the same principles could be employed in connection with still thicker matrices, necessitating the employment of a larger number

of magazines to hold them, in which event, the escapements of the lower magazines would be still farther apart, and the number of intervening links or slides from the 5 several magazines above correspondingly increased in number.

As previously stated, I have shown my invention only in preferred form and by way of example, and as applied to a specific type 10 of machine; but obviously many modifications and alterations therein, and in its mode of adaptation, will suggest themselves to those skilled in the art, without departure from its scope.

15 Having thus described my invention, its construction and mode of operation, what I claim and desire to secure by Letters Patent of the United States, is as follows:

1. In a typographical machine, the combination of a plurality of separate and distinct superposed magazines, each having a series of channels for the type or matrices, and a keyboard mechanism connected simultaneously with all the operative channels 25 of the several magazines.

2. In a typographical machine, the combination of a plurality of magazines, a keyboard mechanism, and means whereby the keyboard mechanism may be connected in 30 its entirety to one magazine, or in part to each of several magazines, at will.

3. In a typographical machine, the combination of a plurality of separate and distinct superposed magazines each having a series 35 of escapements, a corresponding plurality of sets of actuating devices for the escapements, and a keyboard mechanism connected simultaneously to all the actuating devices of the several sets.

40 4. In a typographical machine, the combination of a plurality of superposed magazines each having a series of escapements, the escapements of one magazine being staggered with relation to those of another 45 magazine, and means for operating the escapements.

5. In a typographical machine, the combination of a plurality of superposed magazines each having a series of escapements, 50 those of one magazine being staggered with relation to those of another magazine and a series of escapement actuating devices arranged side by side and divided into sets, one for each magazine, the actuating devices 55 of one set being alternated with those of another set to correspond to the staggered relation of the escapements, for the purpose described.

6. In a typographical machine, the combination of a plurality of superposed magazines each having a series of escapements, 60 those of one magazine being staggered with relation to those of another magazine, and a series of escapement actuating devices di-

vided into sets, the actuating devices of one 65 set being arranged to engage directly with the escapements of one magazine, and connections between those of another set and the escapements of another magazine.

7. In a typographical machine, the combination of a plurality of magazines each having a series of escapements, a series of actuating devices for the escapements, and means whereby the actuating devices may all be connected to the escapements of one magazine, or in part to the escapements of each 75 of several magazines, at will.

8. In a typographical machine, the combination of two superposed magazines each having a series of escapements, those of 80 one series being staggered with relation to those of the other series, operating members connected to the escapements of the upper magazine and located between adjoining escapements of the lower magazine, and a series of actuating devices arranged in operative relation to the escapements of the lower magazine and the connections to the escapements of the upper magazine.

9. In a typographical machine, the combination of the two superposed magazines A¹, A², provided respectively with the escapements B¹, B², the operating slides J connected to the escapements of the upper magazine and extending downwardly between the 95 escapements of the lower magazine, and actuating devices C arranged side by side and adapted to engage the escapements of the lower magazine and the operating slides J for the escapements of the upper magazine.

10. In a typographical machine, the combination of a plurality of superposed magazines each having a series of escapements, and a keyboard mechanism connected simultaneously with all the escapements of the 105 several series.

11. In a typographical machine, the combination of a plurality of stationary magazines, a vertical raceway to receive the type 110 or matrices therefrom, and two receiving elements located between the magazines and raceway and movable into and out of operative relation to a selected pair of magazines.

12. In a typographical machine, the combination of a plurality of magazines, a vertical raceway to receive the type or matrices therefrom, and two receiving elements located between said parts and coöperating with two of said magazines, said elements 120 being movably mounted so as to bring one of them into operative relation to another magazine.

13. In a typographical machine, the combination of a series of superposed magazines 125 each provided with a series of escapements, a series of actuating devices movable vertically into operative relation to the escape-

ments of one magazine, or of a plurality of magazines as desired.

14. In a typographical machine, the combination of a font or series of type or 5 matrices, a plurality of separate and distinct superposed magazines to contain each a portion of said font, and a keyboard mechanism connected simultaneously to both magazines

and adapted to deliver the type or matrices from one or another thereof.

In testimony whereof, I have affixed my signature in presence of two witnesses.

JOHN R. ROGERS.
